FISHING LURE

Thomas A. Denny, Lorain, Ohio, assignor to
Oberlin Canteen, Inc., Oberlin, Ohio

Filed Feb. 20, 1973, Ser. No. 333,781

Term of patent 14 years

Int. Cl. D22—05

U.S. Cl. D22—27

FIG. 4-

FIG. 2-

FIG. 1-

FIG. 3-

FIG. 5 -

FIG. 1 is a top view of a fishing lure, according to my invention, with a hook portion and a spinner blade portion shown in dashed lines for illustrative purposes only;

FIG. 2 is a left side view of the fishing lure shown in FIG. 1;

FIG. 3 is a right side view of the fishing lure shown in FIG. 1;

FIG. 4 is a front end view of the fishing lure shown in FIG. 1; and

FIG. 5 is a rear end view of the fishing lure shown in FIG. 1.

I claim:

The ornamental design for a fishing lure, as shown and described.
